UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-HEATER.

1,292,316.

Specification of Letters Patent. Patented Jan. 21, 1919.

Application filed June 3, 1918. Serial No. 237,869.

To all whom it may concern:

Be it known that I, RUDOLPH HOFFMAN, a citizen of the United States, residing at Kankakee, in the county of Kankakee and State 5 of Illinois, have invented certain new and useful Improvements in Oil-Heaters, of which the following is a specification.

This invention relates to heating stoves of the type known as oil heaters. Such a stove 10 comprises a base, an oil tank, and a shell secured to the base and surrounding the tank.

The object of this invention is to produce improved means for uniting the base and the shell and for supporting the tank in central position with reference to the base and the shell.

In the accompanying drawings Figure 1 is a vertical sectional view of an oil heater embodying the features of my invention. 20 Figs. 2 and 3 are fragmental horizontal sectional views. Fig. 4 is a perspective view of a securing, centering and supporting member.

The annular base 1 comprises supporting 25 legs 2. On the base is an annular upwardly extending flange 3 that fits within the cylindrical shell 4. The base and the shell are secured together by means of a suitable number of members 5. These members may be 30 formed of sheet metal as herein shown. In the construction herein illustrated, each member consists of two plates 6 integrally united by means of a web 7. At the lower portion of each plate 6 is a lug 8 that under- 35 lies the annular upwardly extending flange 3. Each plate 6 is recessed as at 9 to accommodate the flange 3. Above the recess 9 each plate 6 is formed to provide a tongue 10, there being shoulders 11 above and be- 40 low said tongue. These tongues are ar- ranged to extend through slots 12 in the shell 4 and be bent into contact with the outer side of said shell, as shown in Figs. 2 and 3. Said tongues thus serve to secure the mem- 45 bers 5 to the shell 4, with the shoulders 11 in contact with the inner side of the shell. Preferably the upper surface of the lugs 8 is inclined so that the base 1, the shell 4, and the members 5 shall be drawn tightly to- 50 gether when the tongues 10 are inserted through the slots 12 and clenched. The upper inner corner of each member 5 is preferably beveled or cut away as indicated at 55 13 to coöperate with the rounded lower edge of the oil font 14 and thus guide the oil font

into place. The font is provided near its upper portion with an annular outwardly extending flange 15 adapted to rest upon the upper edges of the plates 6.

It will be seen that the members 5 serve 60 to secure the base 1 and the shell 4 together and also provide means for supporting the oil font and for spacing the oil font away from the base and the shell so as to provide an air space around the font. 65

I claim as my invention:

1. An oil heater having, in combination, an annular base having an annular upwardly extending flange, a cylindrical shell into the lower end of which said flange extends, 70 means for securing the base and the shell together comprising a plurality of members formed from sheet metal, each member consisting of two vertical plates connected at one edge by an integral web, a lug on the 75 opposite edge of each plate at the lower end of the plate, said lug having an inclined upper surface to engage the lower side of the base, each plate being recessed to accommodate said flange, each plate being 80 formed above said recess to provide a tongue and a shoulder, there being an opening for said tongue in the shell above said flange, said tongue extending through the opening in the shell and being clenched upon the 85 outer side of the shell with said shoulder in contact with the inner side of the shell, and an oil font adapted to fit between said members and provided with an outwardly extending portion adapted to rest upon said 90 members.

2. An oil heater having, in combination, an annular base, a cylindrical shell, means for securing the base and the shell together comprising a plurality of members each hav- 95 ing a lug at the lower end thereof engaging the base and a pair of tongues, the shell being apertured to receive said tongues so that they may be clenched upon the outer side of the shell, and an oil font adapted to fit between 100 said members and provided with an outwardly extending portion adapted to rest upon said members.

3. An oil heater having, in combination, an annular base, a cylindrical shell, means 105 for securing the base and the shell together comprising a plurality of members formed from sheet metal, each member consisting of two vertical plates connected at one edge by an integral web, a lug on the opposite edge 110

of each plate at the lower end of the plate, said lug engaging the base, each plate having a tongue and a shoulder, said shell being apertured to receive said tongue so that the 5 tongues may be clenched upon the outer side of the shell with said shoulder in contact with the inner side of the shell, and an oil font adapted to fit between said members and provided with an outwardly extending portion 10 adapted to rest upon said members.

4. In an oil heater, an annular base having an annular upwardly extending flange, a cylindrical shell into the lower end of which said flange extends, and means for securing 15 the base and the shell together comprising a plurality of members formed from sheet metal, each member consisting of two vertical plates connected at one edge by an integral web, a lug on the opposite edge of 20 each plate at the lower end of the plate, said lug having an inclined upper surface to engage the lower side of the base, each plate being recessed to accommodate said flange, each plate being formed above said recess 25 to provide a tongue and a shoulder, said shell being apertured to receive said tongue so that the tongue may be clenched upon the outer side of the shell with said shoulder in contact with the inner side of the shell.

30 5. In an oil heater, an annular base, a cylindrical shell, and means for securing the base and the shell together comprising a plurality of members each having a lug at the lower end thereof engaging the base, a

pair of tongues and a shoulder, said shell 35 being apertured to receive said tongues so that they may be clenched upon the outer side of the shell with said shoulder in contact with the inner side of the shell.

6. In an oil heater, an annular base having an annular upwardly extending flange, a cylindrical shell into the lower end of which said flange extends, and means for securing the base and the shell together comprising a plurality of members each having 40 a lug engaging the base and a part adapted to be secured to the shell above the base.

7. In an oil heater, a base, an annular shell rising from the base, and means for securing said parts together comprising a 50 member having a part adapted to operatively engage with the base below the shell and a tongue adapted to be secured to the shell above the base, said tongue being bent into engagement with the shell.

8. In an oil heater, a base, an annular shell supported upon the base, an oil font, and means for supporting the oil font comprising a plurality of members each having a tongue, said shell being apertured so that the tongue may be entered therethrough and bent into engagement therewith, said font having a portion adapted to rest upon said members.

In testimony whereof, I have hereunto 65 set my hand.

RUDOLPH HOFFMAN.
